Primary Examiner — Thomas Johannes*Assistant Examiner* — Catherine Posthauer(74) Attorney, Agent, or Firm — Cynthia R. Miller(57) CLAIM

The ornamental design for a fragrance bottle with cap, as shown and described.

DESCRIPTION

FIG. 1 is a top, front, left side perspective view of my new design for a fragrance bottle with cap;

FIG. 2 is top, front, right side perspective view of the fragrance bottle with cap shown in FIG. 1;

FIG. 3 is a front elevational view of the fragrance bottle with cap, shown in FIG. 1;

FIG. 4 is a rear elevational view of the fragrance bottle with cap, shown in FIG. 1;

FIG. 5 is a right side elevational view of the fragrance bottle with cap, shown in FIG. 1;

FIG. 6 is a left side elevational view of the fragrance bottle with cap, shown in FIG. 1;

FIG. 7 is a top plan view of the fragrance bottle with cap, shown in FIG. 1; and,

FIG. 8 is a bottom plan view of the fragrance bottle with cap, shown in FIG. 1.

The broken lines and the area inside the broken lines in FIGS. 1, 2 and 8 are shown to indicate portions of the fragrance bottle with cap which form no part of the claimed design.

1 Claim, 5 Drawing Sheets(56)
